UNITED STATES PATENT OFFICE.

JOB TATTON, OF MONTREAL, QUEBEC, CANADA, ASSIGNOR TO B. J. COGHLIN & COMPANY LIMITED, OF MONTREAL, CANADA, A CORPORATION.

RAIL DRILL.

Application filed May 28, 1924. Serial No. 716,485.

My invention relates to ratchet driven drills and more particularly to rail drills employed to drill the web of a rail, when attached to the tie.

- 5 The object of my invention is to provide an apparatus that is readily adjustable to the desired position, is firmly secured while operating, is rapid and efficient, and permits the passage of trains without removal.
- 10 The feed is automatic and enables the rapid removal of the bit by means of a hand crank.

15 The apparatus consists of a frame, the front portion of which supports a ratchet driven spindle and the rear portion supports the feed mechanism.

20 Suitable means are provided to secure the frame in position.

25 A special feature is found in the double pawl-ratchet drive.

30 A full detailed description and specification and claims is given hereafter. Reference is made to the accompanying drawings in which:

35 Fig. 1, is a perspective view.
Fig. 2, is a vertical section of the drill adjusted to a rail.

40 Fig. 3, is a vertical cross section at 3—3 of Fig. 2.

45 Fig. 4, is a vertical cross section of the ratchet drive.

50 Figs. 5 and 6, disclose different positions of the ratchet drive from Fig. 4.

The frame 1, has the front standard 10, and the rear standard 11.

55 The front standard 10, provides the ratchet drive casing and supports the bearings of a rotatable bushing 12, in which is mounted the drill spindle 2.

60 The drill spindle 2, carries the chuck 21, at its forward end and a thrust bearing 23 in the guide block 22 at its rear end.

65 The guide block 22 travels on bar 24, which connects with both standards 10 and 11.

70 The ratchet 3, is fitted on the middle portion of the bearing bushing 12, which is held securely by the collar 120.

75 Above the ratchet 3, the pawl block 31, is journalled in the casing on the feed spindle 4, to which it is secured.

80 The feed spindle 4, extends to the rear standard 11 in which it is journalled and carries a crank lever 41.

The rear standard 11, provides bearings 55 for the internally threaded sleeve 52, which is held in place by the collar 520.

85 The feed screw 5, meshing with the sleeve 52, terminates in a cup 51, which is secured to the guide block 22.

90 The feed ratchet 54 is fitted on the sleeve 52, and is operated by one or more pawls 55, journalled to the crank 41.

A hand crank 53, on the outer end of the sleeve 52, provides rapid adjustment of the 95 drill spindle 2.

The frame on front standard 10, has side projections 101, with adjustment screws 102, to bear on the inner flange of the rail 8.

100 A pair of clamp bars 6, provided with hooks 60, to embrace the outer flange of the rail 8, have lugs 63, to which are journalled a wedge shaped cross bar 64.

105 The frame on front standard 10, has wedge shaped slots 108, adapted to secure 75 the cross bar 64.

110 Dogs 61, are provided on the clamp bars 6, adapted to grip the inner flange of the rail 8, and sliding wedges 62, complete the 80 means of rigid adjustment.

115 While the detail construction of the ratchet drive may vary I have provided a novel form which is shown in Figures 4, 5, 6.

120 This consists in a pentagonal ratchet 3, with rounded teeth 30 mounted on the bearing bushing 12, through which the drill 85 spindle 2 passes.

125 Above the ratchet 3, the pawl block 31, is mounted on the square portion 40, of the feed spindle 4, journalled in the casing of 90 the standard 10.

130 The upper edge of the casing has two 100 downwardly inclined edges 100.

135 The pawl block 31, has projecting edges 311, inclined upwardly adapted to bear on 95 the edges 100, and limit the stroke of the pawl block 31, operated by the lever 7.

140 Two forms of pawls 32 and 33 are pivoted in the lower edge of the pawl block 31. The 100 pawl 32 has a curved jaw at its end to embrace the teeth 30, a coil spring 320, in the lower edge of the pawl block 31, tends to press the pawl 32, against the ratchet 3.

145 The pawl 33, has a central curved jaw and an extension the length of one side of 105 150 the ratchet and carries a spring 330, bearing on the casing wall.

155 The operation of the ratchet drive is as

follows. When the pawl block is at the end of its stroke to the right as shown in Fig. 6, the pawl 33, due to the tension of the spring 330, grips the tooth of the ratchet 3.

5 The stroke to the left then begins and the pawl 33, drives the ratchet 3, until the central jaw embraces the next tooth, see Figure 4, continuing the stroke, the central jaw drives the ratchet 3, until it is stopped 10 by the edge 311, of the pawl block 31, meeting the edge of the casing 100, at which stage the jaw of the pawl 32, grips the next tooth as seen in Figure 5.

15 During the entire stroke to the right the pawl 32, drives the ratchet 3, till the position shown in Figure 6, is again reached.

20 The rail drill as above described is adjusted in position as shown in Figure 1, by hooking the clamps 6, under the rail 8, to 25 the outer flange, the dogs 61 and the wedges 62 are then clamped on the inner flange.

25 The cross bar 64, provides a guide for lateral adjustment of the drill when it enters the slot 103. The set screws 102, secure the frame rigidly in position to operate.

30 The bit is inserted in the chuck 21, and the crank 53, brings it up to the web of the rail.

35 The feed pawl 55, is let down on the ratchet 54, and the operator starts to work the lever 7.

40 Each complete stroke of the lever 7, drives the feed ratchet one tooth and the sleeve rotates moving the feed screw forward and advancing the bit.

45 What I claim is:—

1. In a rail drill the combination of a frame having front and rear standards, a ratchet driven drill spindle journalled to the front standard, a thrust bearing thereto carried in a guide block, a threaded feed screw secured to the guide block extending rearwardly through an internally threaded sleeve in the rear standard, a crank to operate sleeve, a ratchet drive to rotate sleeve, with means to adjust the frame in position on the side of a rail, having pivoted hooked clamp bars with sliding dogs, adapted to pass under and grip the rail base.

50 2. In a rail drill the combination of a frame having front and rear standards, forward projections to base of front standard provided with adjustment screws adapted to bear on the rail flange, a ratchet driven drill spindle journalled in the front standard, a thrust bearing thereto carried in a guide block, a threaded feed screw secured to the guide block extending rearwardly through an internally threaded sleeve in the rear standard, a crank to operate sleeve, a ratchet drive to rotate sleeve, with means to adjust the frame in position on the side of a rail, having pivoted hooked clamp bars with sliding dogs, adapted to pass under and grip the rail base.

55 3. In a rail drill the combination of a frame having front and rear standards, forward projections to base of front standard provided with adjustment screws adapted to bear on the rail flange, a ratchet driven drill 70 spindle journalled in the front standard, a thrust bearing thereto carried in a guide block, a threaded feed screw secured to the guide block extending rearwardly through an internally threaded sleeve in the rear 75 standard, a crank to operate sleeve, a ratchet drive to rotate sleeve, with a rail clamp comprising two hooked clamp bars with lugs pivoted to a wedge shaped cross bar, having sliding dogs and wedges on the clamp bars, 80 adapted to pass under and grip the rail base.

85 4. In a rail drill the combination of a drill spindle, a chuck thereon, a thrust bearing thereto, a ratchet drive to operate the spindle, a guide block supporting the thrust bearing, a guide rail thereunder, with a feed screw, a capped end thereto secured to the guide block, an internally threaded sleeve meshing with the feed screw, a ratchet drive 90 thereto operated by the drill ratchet drive, and a hand crank to operate the sleeve.

95 5. In a rail drill the combination of a drill spindle, a chuck thereon, a thrust bearing thereto, a bearing bushing mounted on 95 the drill spindle, a ratchet secured to the bearing bushing, a pawl block adapted to be rocked by a hand lever, pawls pivoted to the pawl block adapted to rotate the ratchet, a guide block supporting the thrust bearing 100 a guide rail thereunder with a feed screw, a cupped end thereto secured to the guide block, an internally threaded sleeve meshing with the feed screw, a ratchet drive thereto operated by the drill ratchet drive, and a 105 hand crank to operate the sleeve.

110 6. In a rail drill the combination of a drill spindle, a chuck thereon, a thrust bearing thereto, a ratchet drive to operate the spindle, a guide block supporting the thrust bearing, a guide rail thereunder, with a feed screw, a cupped end thereto secured to the guide block, an internally threaded sleeve meshing with the feed screw, a ratchet drive 115 thereto comprising a ratchet secured to the sleeve, a feed spindle operated by the pawl block, a crank lever on the end of the feed spindle, a pawl pivoted to the crank lever adapted to drive the feed ratchet and a hand crank to operate the sleeve, mounted on a frame having front and rear standards with 120 adjustable hooked clamp bars pivoted to the front standard and adapted to pass under and grip the rail base.

125 7. In a rail drill the combination of a drill spindle, a chuck thereon, a thrust bearing thereto, a bearing bushing mounted on the drill spindle, a ratchet secured to the bearing bushing, a pawl block adapted to be rocked by a hand lever, pawls pivoted to the 130

pawl block adapted to rotate the ratchet, a guide block supporting the thrust bearing, a guide rail thereunder, with a feed screw, a cupped end thereto secured to the guide block, an internally threaded sleeve meshing with the feed screw, a ratchet drive thereto comprising a ratchet secured to the sleeve, a

feed spindle operated by the pawl block, a crank lever on the end of the feed spindle, a pawl pivoted to the crank lever adapted to 10 drive the feed ratchet and a hand crank to operate the sleeve.

JOB TATTON.
